LOUISE ZOLLARS, OF HOLLYWOOD, CALIFORNIA

HAIR DRIER

Application filed December 1, 1931. Serial No. 578,235.

This invention has to do with drying apparatus and is more particularly related to that type of drying apparatus ordinarily used in beauty parlors and the like for drying hair. Hair driers of this nature as ordinarily constructed, comprise a housing or a hood member having a suitable heating element mounted therein and associated with a fan for directing a current of air through the heating element and into a head space formed in the front end portion of the hood.

Means are provided for varying the temperature of the heating element and in some instances means are provided for varying the speed of the fan so as to regulate the velocity of air flowing through the hood. Driers of this nature have the disadvantage of subjecting the occupant of the drier to a current of warm or hot air which circulates about the face and the neck over a substantial period of time, depending upon the time required to properly dry the hair.

It is the primary object of this invention to produce a drier of the class described which is constructed so that warm air may be directed upon the hair of the occupant, and which is provided with means for selectively directing a current or currents of cold or cool air into the portions of the head space where no drying action is needed.

More specifically my invention comprises a drier of the class described consisting of a hood having a head space therein and provided with means for directing a current of warm air through the central portion of the hood and into engagement with the hair.

In addition to such means I provide an isolated air duct preferably contained within the housing and adapted to carry cool or cold air into the front upper end portion of the head space.

In addition to this air duct I provide another isolated air duct preferably situated in the bottom portion of the housing which

directs a current of cold air into the lower portion of the head space.

It will be seen that the first air duct mentioned above directs a current of cool air across the face of the occupant of the drier and the second air duct directs a current of cool air about the neck of the occupant.

The air ducts just described are both provided with valve means for regulating the flow of air therethrough.

The details in the construction of a preferred form of my invention, together with other objects attending its production will be best understood from the following description of the accompanying drawing which is chosen for illustrative purposes only, and in which—

Fig. 1 is an elevational view partly in section showing a preferred form of my invention;

Fig. 2 is a sectional view taken in a plane represented by the line 2—2 in Fig. 1;

Fig. 3 is an end elevation which may be considered as having been taken in the direction of the arrow 3 in Fig. 1;

Fig. 4 is a perspective view showing a preferred form of valve plate which may be used in regulating the quantity of air flowing through the cold air ducts, and

Fig. 5 is a fragmentary detail view illustrating means for controlling the air valves just mentioned.

More particularly describing the invention as herein illustrated, reference numeral 11 indicates a drying apparatus which consists of a shell or housing 12 which may be made in any cross sectional shape but is shown as being constructed as rectangular or substantially square.

This shell is provided at its rear portion with a circular flange 13 which supports a fan cage 14, the fan cage having a motor 15 mounted thereon, said motor being provided with shaft 16 which extends inwardly into

a so-called fan chamber 17 formed in the rear end portion of the shell 12 and has a fan 18 provided thereon, within the fan chamber.

5. The shell 12 may be supported in any suitable manner but is shown as adjustably supported by means of ears 19 which are shown as being mounted in the fan cage and which pivotally engage a bracket 20 mounted upon a standard 21 which is adjustably received in a vertical leg 22, such leg being provided with a suitable stand not shown.

10. The front end portion of the shell 12 is provided with what I may term a hood member 24 which extends forwardly to form a head space 25.

15. The central portion of the shell is provided with what I may term a hot air barrel 26 which is shown as having its rear portion supported in the shell by a supporting plate 28.

20. The upper end portion of the shell is provided with a partition plate 29 which is spaced a substantial distance from the shell proper and cooperates therewith to form a duct or passage 30 through which cool air may be delivered from the fan chamber 17 to a point indicated at 31 where such cool air leaves the duct and is directed downwardly across the head space from a substantially vertical section 32 of the duct, such section having an opening in its lower end.

25. The bottom portion of the shell is provided with a partition member 34 which is spaced a substantial distance above the bottom portion so as to form another air duct which leads from the air chamber 17 to the rear bottom portion of the head space.

30. This duct, which is indicated by reference numeral 35, has ports 36 provided in its forward edge, such ports being adapted to direct the cool or cold air, coming direct from the fan, about the neck of an occupant of the drier which is shown in dot and dash lines in Fig. 1.

35. The air coming from the duct 30 is directed downwardly across the face of the occupant of the drier and for the purpose of directing warm air against the hair of the occupant, I provide within the barrel 26 an air directing dome 40 which is supported in the barrel by a plurality of fins 41. This dome is situated with its widest diameter away from the fan and the widest diameter of the dome is spaced inwardly from the inner surface of the barrel 26.

40. Mounted on the periphery of this dome, I provide a heating element indicated by reference numeral 42, this element being connected through a conductor 43 with a rheostat box 44 which may be employed to regulate the current delivered to the heating element and thereby regulate the temperature of such element.

45. The air which passes from the fan chamber

17 through the heating element 42 is directed in a general inward direction by means of a baffle member 45 which is constructed in the nature of a constricted shell having a narrow throat, such shell being adapted to direct the air, which has been heated by the heating element, onto the hair of the occupant of the drier:

50. In order that the cool air passing through ducts 30 and 35 may not be heated by the heating element or by conduction through the central barrel, I provide suitable insulating means which separate the barrel from the partition members 29 and 34. This insulation may be any type of commercial insulation but in the form shown I have provided the necessary insulating medium by separating the barrel 26 a slight distance from the respective partition members 29 and 34, thus providing a dead air space therebetween which forms a very effective insulating medium.

55. In order to prevent a loss of air from the drier through the opening through which the conduit 43 is lead from the heating element, I provide a tube 47 which is provided with a packing member 48 in its upper end portion.

60. For the purpose of controlling the quantity of air delivered to the top and bottom portions of the head space through the ducts 30 and 35, I provide such ducts with valve means generally indicated by reference numerals 49 and 50 respectively. These valves may be of any preferred type, but for simplicity and economy in construction I choose to form the valves of substantially flat plates best shown in Fig. 4 and indicated by reference numeral 51.

65. These plates have their side portions upturned to form guide flanges 52 and 53, the guide flange 53 being provided with a knob 54 adapted to extend through a slot 55 in the side of the drier shell.

70. It will be observed that these plates 51 may be moved from an extreme open position, as shown in Fig. 1, to a position at which the rear edges of the plates engage the vertical plate portion 57 of the shell or housing. When in this extreme rear position there will be no circulation of cool air through the ducts. These valve members are independently operable so that the cool air can be controllably delivered to both the front and rear portion of the head space.

75. In operation it will be observed that when the fan is being driven by the motor 15, cold air is drawn into the fan space through a screen indicated at 60. Part of such cold air is thrown outwardly by the fan and passes through the ducts 30 and 35, the quantity of such air being controlled by the position of the valve members 49 and 50. The remainder of the air drawn into the fan space by the fan, is forced inwardly over the dome 40 and through the heating element 42 which warms it to the desired temperature, depending

upon the temperature of the heating element and the velocity at which the fan is operated. This warm air is then directed into the head space as indicated by the arrows shown in 5 Fig. 1.

From the above description, it will be seen that this invention contemplates a drier having a head space which is provided with means for directing two or more currents of 10 air into the head space, such currents of air being of different temperatures. This construction, as pointed out above, has the advantage of providing means whereby warm or hot air may be directed against the hair 15 and a current of cold or cool air that may be directed against those portions of the head which are not to be dried.

It is to be understood that while I have herein described and illustrated one preferred 20 form of my invention, the invention is not limited to the precise construction described above, but includes within its scope any changes which fairly come within the spirit of the appended claims.

25 I claim as my invention:

1. A hair drier embodying: a housing having a head space in the front portion thereof and a fan chamber in the rear portion thereof; air heating means in said housing; means 30 for conducting air from said fan chamber through said heating means and into the central portion of said head space; and a cool air conduit in the top of said housing for conducting cool air from said fan chamber 35 to the front upper portion of said head space; said cool air conduit terminating in an opening arranged for directing air from said conduit downwardly across the front of said head space and across the face and 40 cheeks of a head therein.

2. A hair drier embodying: a housing having a hood formed with a head space in the front portion thereof and a fan chamber in the rear portion thereof; air heating means 45 in said housing; means for conducting air from said fan chamber through said heating means and into the central portion of said head space; a cool air conduit in the top of said housing for conducting cool air from 50 said fan chamber to the front edge of said hood; and insulating means interposed between said cool air conduit and said air heating means, said cool air conduit terminating in an elongated opening arranged to direct 55 cool air downwardly across the front of said head space and across the face and cheeks of an occupant of said drier.

60 3. A hair drier embodying: a housing having a hood formed with a head space in the front portion thereof and a fan chamber in the rear portion thereof; air heating means in said housing; means for conducting air from said fan chamber through said heating means and into the central portion of said 65 head space; and a cool air conduit in the bot-

tom of said housing extending from said fan chamber to the lower edge of said hood, said cool air conduit having an opening at the lower edge of said hood for directing cool air across the lower edge of said head space and across the neck and shoulders of an occupant thereof.

4. A hair drier embodying: a housing having a head space in the front portion thereof and a fan chamber in the rear portion thereof; air heating means in said housing; means for conducting air from said fan chamber through said heating means and into the central portion of said head space; a cool air conduit in the bottom of said housing for conducting cool air from said fan chamber to the lower edge of said head space; and insulating means interposed between said air heating means and said cool air conduit.

5. A hair drier embodying: a housing having a head space in the front portion thereof and a fan chamber in the rear portion thereof; air heating means in said housing; means for conducting air from said fan chamber through said heating means and into the central portion of said head space; a cool air conduit in the bottom of said housing for conducting cool air from said fan chamber to the lower edge of said head space; and valve means for opening and closing said cool air conduit.

6. A hair drier embodying: a housing having a head space in the front end thereof; a fan chamber in the rear portion of said housing; a fan in said fan chamber; air heating means in said housing; means for conducting air from said fan chamber through said heating means to said head space; a cool air duct extending along one edge of said housing from the fan chamber to the head space; and valve means for opening and closing said cool air duct, said valve means comprising a plate member slidably mounted in said cool air duct and adapted to be moved across said fan chamber.

7. A hair drier embodying: a housing having a hood formed with a head space in the front portion thereof and a fan chamber in the rear portion thereof; a hot air conduit in said housing for delivering air from said fan chamber into the central portion of said head space; a heating element in said hot air conduit; and cool air conduits leading from said fan chamber to said hood and separated from said hot air conduit, said cool air conduits having openings in said hood arranged so as to direct cool air across the front and bottom of said head space.

8. A hair drier embodying: a housing having a head space formed in the front portion thereof and a fan chamber in the rear portion thereof; a hot air conduit in said housing for delivering air from said fan chamber into the central portion of said

head space; means for heating the air passed through said hot air conduit; cool air conduit means in said housing for delivering cool air from said fan chamber to the edge 5 of said head space and directing said cool air across the front and bottom of said head space, said cool air conduit means being separated from said hot air conduit.

In testimony whereof, I have hereunto set 10 my hand at Los Angeles, California, this 20th day of November 1931.

LOUISE ZOLLARS.
